US00D601088S

(12) **United States Design Patent**
Scheucher

(10) **Patent No.:** **US D601,088 S**
(45) **Date of Patent:** **** Sep. 29, 2009**

(54) **BATTERY PACK**

(76) Inventor: **Karl F. Scheucher**, 7136 Eagle Rd.,
Waite Hill, OH (US) 44094

(**) Term: **14 Years**

(21) Appl. No.: **29/280,875**

(22) Filed: **Jun. 8, 2007**

(51) LOC (9) Cl. **13-02**

CLAIM

The ornamental design for a battery pack, as shown and described.

DESCRIPTION

FIG. 1 is a front perspective view of my design.

FIG. 2 is a left side view of my design.

FIG. 3 is a right side view of my design.

FIG. 4 is a top view of my design.

FIG. 5 is a bottom view of my design.

FIG. 6 is a front view of my design.

FIG. 7 is a rear view of my design.

FIG. 8 is an enlargement of a portion of the rear view of my design; and,

FIG. 9 is a rear perspective view of my design.

The broken line showing of the circle and line in FIG. 7 is included for the purpose of indicating the enlarged area shown in FIG. 8 and forms no part of the claimed design.
